TELEMETRIC INDICATOR OF CORRECTED
ANGULAR POSITIONS

Albert Stiegler, Berlin-Marienfelde, Germany,
assignor to Telefunken Gesellschaft für Draht-
lose Telegraphie m. b. H., Berlin, Germany, a
corporation of Germany

Application September 5, 1939, Serial No. 293,480
In Germany September 17, 1938

4 Claims. (Cl. 250—11)

In the installation of direction-finders, marine or aircraft, it is often desirable to mount rotatable directional antenna systems at some distance from the control point or observer's station. In cases of this kind, the position of the antenna may be subject to remote control actions sent out from the observer's station. In any event, the position of the antenna must be indicated at the control point. Mechanical and electrical remote control arrangements have been disclosed in the prior art and some of them have been tried out in practice.

A certain difficulty in this connection resides in the necessary compensation or correction of the deviational or quadrantal error. It is known from practice that the uncorrected radio bearing obtained from normal direction-finding requires correction because the direct radiation, coming from a beacon whence bearings are to be taken, combines with the waves reflected from the hull or other parts of the craft. The combined waves produce a directional indication which differs from the actual beam or beacon direction by a certain quadrantal error which may either be positive or negative and which is a function of the bearing angle at a given angular position of the directional antenna. To compensate for this error, mechanical means have been suggested in the prior art in which the bearing indication means is moved so as to lag or lead the rotation of the directional antenna by angle corresponding to the quadrantal error.

In using directional antenna systems as heretofore known which are mechanically remote controlled, for instance, by means of a flexible shaft, the error correction has been applied and introduced directly at the control point. In electrical remote control such an arrangement is not well adapted because the power required for the actuation of the radio compensator would have to be transmitted back from the remote control driving motor to the control place either mechanically or electrically.

According to the invention, all of these drawbacks are avoided in telemetric arrangements with synchronous systems in that the power required for error correction is furnished at the sending end, and furthermore the correction consisting of a corresponding relative shift or rotation of a stator in respect to the cooperating rotor of a telemetric device such for example as a "Selsyn" motor. The telemetered value, as will thus be seen, is the true bearing so that at the receiving end no corrections will have to be in-

troduced and only the power required for telemetric indication will have to be transmitted.

The invention will be described by reference to the accompanying drawing in which Figure 1 is 5 a schematic circuit diagram of one form of telemetric device embodied in the invention, and Figures 2a and 2b are perspective views illustrating, respectively, a transmitter and receiver for transmitting and receiving the bearing indications. Similar reference numerals will be used to indicate similar elements in the several figures.

In Fig. 1 is shown an embodiment of the basic idea of the invention, a synchronous system of 15 the kind used for telemetric work in which the stators S1 and S2 of the transmitter G and the receiver E are connected delta fashion and are united with each other. The rotors R1 and R2 are connected in parallel to a source of alternating potential supply. Relative rotation of the rotor in reference to the stator at the sending end, as well known in the art, will be telemetered and indicated at the receiver with angular fidelity. Now, according to the invention, the rotor 20 of the transmitter is turned in synchronism with the directional antenna system A (see Fig. 2a) while the stator is turned in clockwise or counter-clockwise direction corresponding to the quadrantal error correction value required at each 25 specific rotor position. For instance, if the relative position of the stator and the rotor as shown in the drawing corresponds to an error *f*, which, by way of example, may be assumed to be in the longitudinal direction of the craft, then, upon 30 rotating the loop out of this direction to another a bearing angle *q*, there will arise a certain error. If this error is positive, then the stator, by automatic control means, should be turned in counter-clockwise sense an amount of error *f* so that 35 rotor and stator of the transmitter are turned in reference to each other an amount equal to the true angle *p* = *f* + *q*. This relative angle of position of rotor and stator is sent to the receiver 40 where the true bearing *P* will be indicated.

Fig. 2a shows a transmitter device in which a 45 directional antenna system A is coaxially mounted with the rotor R1 of the transmitter and the compensator cam K. By a crank lever system H the stator, as well known in the art, is turned in 50 relation to the rotor an angle corresponding to various quadrantal errors. The relative angular position between rotor and stator is transmitted to the receiver E (Fig. 2b) with the result that rotor R2 conjointly with pointer Z is caused to

turn the true bearing angle P which is indicated on the scale S_k .

It will be understood that the arrangement hereinbefore disclosed is not to be restricted to the exemplified embodiments hereinbefore described by reference to the drawing nor to the particular practical purpose herein mentioned. In fact this arrangement will be useful advantageously wherever an angular position is to be telemetered or transmitted to a distant point and where there is a necessity for correcting the position as a function of an angle. It is also possible to include signal errors of the synchronized system itself in the correction or compensator curve so that these are also eliminated.

I claim as my invention:

1. A telemetric indicating system for a radio direction finder subject to quadrantal errors, in which the transmitter and receiver each include an electromagnetic rotor and an electromagnetic stator, means for moving the rotor of the transmitter in accordance with a position to be indicated, means for moving the stator of the transmitter as a function of said quadrantal errors, and means electrically connecting the transmitter and receiver for synchronized operation of said rotors so that the rotor at the receiver indicates said position independent of said quadrantal errors.

2. A telemetric indicating system for indicating at a remote point radio bearings subject to the quadrantal errors of a directional antenna in which the telemetric transmitter and telemetric receiver each include an electromagnetic rotor and an electromagnetic stator, means for moving the rotor of the transmitter in accordance with the position of said directional antenna, means

for moving the stator of the transmitter to compensate for the quadrantal errors of said directional antenna, and means electrically connecting the transmitter and receiver for synchronized operation of said rotors so that the rotor of said receiver indicates said bearings independently of said quadrantal errors.

3. A telemetric indicating system for a radio direction finder subject to quadrantal errors, in which the telemetric transmitter and receiver each include an electromagnetic rotor and an electromagnetic stator coaxially mounted, means for moving the rotor of the transmitter in accordance with a position to be indicated, means including a compensating cam for moving the stator of the transmitter as a function of said quadrantal errors, and means electrically connecting the transmitter and receiver for synchronized operation of said rotors to indicate said receiver said position free from said quadrantal errors.

4. A telemetric indicating system for apparatus subject to periodically repeated errors in which the transmitter and receiver of said system each include an electromagnetic rotor and an electromagnetic stator, means for moving the rotor of the transmitter in accordance with the indication to be transmitted, means for moving the stator of the transmitter as a function of said periodically repeated errors, and means electrically connecting the transmitter and receiver for synchronized operation of said rotors so that the rotor at the receiver gives the proper indication independent of said periodically repeated errors.

ALBERT STIEGLER.
